CARBURETOR

Russell E. MacKenzie, Detroit, Mich., assignor to
Detroit Lubricator Company, Detroit, Mich., a
corporation of Michigan

Application January 30, 1932. Serial No. 589,817

10 Claims. (Cl. 261—49)

My invention relates to new and useful improvements in carburetors, and more particularly to a carburetor for use with or for supplying fuel to an internal combustion engine.

5 An object of my invention is to provide a carburetor in which the throttle or other fuel mixture flow controlling means will be automatically regulated or adjusted to the positions for maximum efficiency for certain given air to fuel ratios
10 without affecting the normal operation of the controlling means.

The invention consists in the novel construction and combination of parts, to be more fully described hereinafter, and the novelty of which will be particularly pointed out and distinctly claimed.

In the accompanying drawings to be taken as a part of this specification, I have fully and clearly illustrated a preferred embodiment of my invention, in which drawings—

Figure 1 is a view in side elevation of a carburetor embodying my invention, and having a portion of the side wall broken away to show the internal construction;

25 Fig. 2 is a view in end elevation looking from left to right of Fig. 1, and partly in section on the line 2-2 thereof;

Fig. 3 is a detail top plan view on the line 30 of Fig. 2, showing the normal relative positions of certain of the elements, but with the carburetor reversed from the position of Fig. 1;

Figs. 4 and 5 are detail views similar to Fig. 3, but showing other relative positions of the elements, namely, a "warming-up" and a "starting" position respectively;

Fig. 6 is a view in reduced size and partly in vertical central section, taken transversely to Fig. 1 to show the air control vanes; Fig. 7 is an enlarged detail view, taken on the

Fig. 8 is a diagrammatic view in section, showing

Fig. 6 is a diagram showing the relation of the ports and passages.

Referring to the drawings by characters of reference, 1 designates, generally, the hollow

45 casting or body of a carburetor having a passage-way 2 therethrough defining a mixing chamber

or passage having a main air inlet 3 and a mixture outlet 4. The inlet 3 is preferably separated from the mixing chamber by cooperable and separable valve plates or vanes 5 having cooperating edge recesses defining a primary air

55 flow port 6. Within the passageway there is a vertical fuel nozzle 7 operatively connected to the vanes 5 for reciprocation thereby by lever arms (not shown) which engage in the nozzle

groove or recess 7^a, and having an adjustable metering pin 8 controlling the discharge of fuel from the nozzle. The nozzle is supplied through a passage 9 with fuel from a constant level float chamber or reservoir 10 having a fuel inlet 10^a 60 controlled by a float operated valve (not shown), the same being well known in the art. The outlet from the mixing chamber is controlled by a throttle valve 11, preferably of the butterfly type, fixed on a shaft 12 journaled in the side 65 walls of the casing 1. One end of the shaft 12 projects through the casing and has fixed thereon above the reservoir an operating lever 13 having arms 14, 15 extending oppositely from the shaft.

On the casing 1 there is a lateral, substantially vertical extension 16 positioned below the projecting throttle shaft end and above the reservoir. The extension 16 comprises a valve casing having a substantially vertical cylindrical bore 17 therethrough. A conduit 18 extends or opens from the bore 17, as at 19, through the extension and casing walls and opens or discharges into the passageway 2 above or on the outlet side of the throttle at a port 20. A conduit 21 extends or opens from the bore 17, as at 22, at a point spaced circumferentially from conduit opening 19, and discharges through a nozzle 23 which projects substantially radially into the passageway 2 below or on the inlet side of the throttle and above the vanes. A cylindrical valve member 24 is fitted for rotation in the bore 17, projecting above and below the extension 16, and is

held against endwise or vertical movement by a screw 25 or the like which seats in a circumferential groove or recess 26 in the valve member. Within the valve member 24 there is a cylindrical fluid chamber 27 having a concentric passage or aperture 28 through its bottom wall, the passage opening into a concentric cylindrical cavity or recess 29 in the lower end of the valve member. The top of the chamber 27 is closed by a freely reciprocable close fitting cylindrical valve plug 30 which is connected by a link or push rod 31 to the lever arm 15. Depending from and fixed to the plug valve 30 there is a hollow plunger or piston rod 32 which extends downward with a close but free sliding fit through aperture 28 and terminates in the float chamber 10. A cover member 33 is provided for chamber 10 and has an aperture therethrough surrounding rod 32 and through which a pump cylinder casing 34 depends, the casing having a lateral flange 35 which rests on the member 33 to support the casing 34 therefrom. Through the bottom wall of the casing 34 which terminates adjacent the bottom 110

wall of the reservoir 10, there is a fuel inlet port 36 controlled by an inward or upward opening check valve 37. Within the casing 34 there is a piston 38 having an aperture 39 therethrough aligned with the bore 40 of plunger rod 32 and which engages the rod 32 for reciprocation thereby. The piston is held in engagement with and forced to follow the rod 32 by a compression spring 41. The bottom end of the recess 29 is closed by a sleeve member 42 which surrounds the rod 32 and which has a substantially vertical cylindrical wall or flange 43 which is sealed to the inner or top end wall of recess 29, the flange being spaced laterally from both the recess side wall and from the rod 32. The top end of the pump casing is closed by a cover member 44 on which is seated the hub portion of an adjusting lever 45 which surrounds the lower end of valve member 24 and which is fixed thereto for rotation of the valve member thereby. The extension 16 has at one side of the bore 17, a vertical bore 47 defining an air inlet chamber and fuel catching cup or trap which is in communication at its bottom end by a passage 48 with the recess 29 around the flange 43, through which are one or more ports 49 adjacent the bottom of the recess.

Through the vertical side wall of the valve member 24, there is a port 50 which is normally in register with a port 51 adjacent the top of and leading from the air inlet chamber 47 which is open to the atmosphere through a lateral port 52, also adjacent its top. The chamber 27 is normally in communication with the conduit 35 21 by means of a port 53 in the valve member. Also through the wall of the valve member there are ports 54, 55 which are cooperable with but normally circumferentially spaced respectively from the inlets 19 and 22 of the conduits 18 and 40 21 respectively. The sizes of the diameters of these fuel flow controlling ports 53, 54 and 55 may be, for example, 0.070 inches, 0.125 inches, and 0.076 inches respectively. Through the wall of the tubular piston rod 32 there are one or 45 more apertures 56 within the chamber 27 and adjacent plug 30 for discharge of fuel from the bore or conduit 40 into the chamber 27. Also through piston rod 32 there is a port 57 which is normally closed and sealed by the side wall 50 of passage 28.

The free end of lever arm 14 has or carries an adjustable abutment 58, such as a screw, or the like, which is cooperable with the casing 16 to limit closing movement of the throttle valve, 55 the screw preferably being set so as to limit throttle closing to a position of coincidence with a line, as *a*, Fig. 2, such that a point *a'* on the throttle edge will be spaced from the side wall of passageway 2 about seven thousandths (0.007) of an inch. The top edge of the casing 16 is preferably recessed, as at 58^a, opposite the lever arm 14 to expose the periphery of the valve member 24, which is provided with a cam means accessible through the casing-edge recess. The 65 cam is preferably formed by cutting away the external surface of the valve member adjacent its top end to provide two vertical plane faces or flats 59, 60 at an angle of substantially ninety degrees to each other, and meeting each other substantially at the external surface of the cylindrical valve member. A cam follower member 61 is carried by the lever arm 14, and is preferably a screw or externally threaded pin or the like adjustably threaded in and projecting from 70 the arm 14 through the recess 58^a for cooperable engagement with the cam faces or flats 59, 60. The meeting line or high point of the cam, designated 62, between the diverging cam faces is so positioned relative to the valve ports and the pin 61 that when the port 55 is in line or register with the conduit 21 which feeds into the space between the vanes and the throttle, the end of pin 61 will be in engagement with or riding on the cam high point or line 62. The diameter of the valve member is preferably such that when the cam faces are formed as above described, and the pin 61 is adjusted, the throttle valve 11 will be moved into the line designated *c*, Fig. 2, and the throttle edge will be at a point as *c'*, which is a throttle opening of substantially two-hundredths (0.02) of an inch upon rotation of the valve member 24 to bring port 54 and conduit inlet opening 19 of priming conduit 18 into alignment or register, as in Fig. 5. This adjustment of pin 61 will cause the throttle to be moved into the line *b* with the throttle edge at the point *b'* when the cam follower pin 61 is in engagement with or riding on the cam high point 62. The valve member adjusting lever 45 is preferably provided with spaced stop or limiting arms 63, 64 which cooperate with a stop member 65, which may be the head portion of one of the reservoir cover securing screws 66. The arms 63, 64 are so spaced that when arm 64 engages the stop member 65, the valve member 24 will be in normal position with the port 53 in register with nozzle 23, and that when arm 63 is in engagement with member 65 the valve member will have been rotated to bring port 54 into register with priming conduit inlet 19. The port 50 is so positioned that it will be out of register with the air passage or port 51 and be sealed when the port 55 has communication with nozzle passage 21. A spring 67 or the like is provided, having one end engaging the carburetor casing 1 and its other end fixed to the lever 45 so as to normally urge the valve member toward normal position, Fig. 3. The spring 67 is preferably of the helical type and is compressed between the extension 16 and the top face of lever 45, so that it acts to hold the pump casing 34 and cover 44 firmly in place.

The surface of the liquid fuel in the float chamber 10 is open to the atmosphere through the port 68 between the cover 33 and the float chamber wall.

The operation of the carburetor is as follows: With the throttle valve 11 in normal "idling" or closed position, that is, in the line *a*, the operating lever 45 is turned or rotated clockwise of Fig. 3 to the position shown in Fig. 5, which may be termed the engine starting position. Rotation of lever 45 to its limit, determined by engagement of arm 63 with stop 65, will close the air inlet port 50 and fuel discharge ports 53 and 55, and will open fuel port 54, placing it in register or communication with conduit inlet opening 19 supplying the priming charge through port 20 beyond or posterior to the throttle, the lever rotation being opposed by spring 67. This operation will also serve to move the throttle valve to an open position by means of the connection between the valve member 24 and the throttle shaft 12. In particular, as the member 24 is turned, the cam face 59 will engage the cam follower pin 61 and move the pin outward until the pin 61 rides on the cam point 62, i. e., to the position of Fig. 4, thus rotating the throttle shaft through the medium of the lever arm 14 and 130 135 140 145 150 155 160 165 170 175 180 185 190 195 200 205 210 215 220 225 230 235 240 245 250 255 260 265 270 275 280 against the force of spring 41, with the throttle valve being moved toward open position and into the line b. As the lever 45 is moved further, beyond the position of Fig. 4, the pin 61 rides off point 62 and will follow the cam face 60 and move inward under the force of the spring 41, which acts through link 31 and the lever 13 and until the stop arm 63 strikes stop 65, as in Fig. 5. The throttle valve 11 will now have been moved, due to movement of pin 61, toward closed position from the line b to the position indicated by the line c, which is the throttle position which will result in maximum carburetor efficiency for the full choke position and for the ratio of air to fuel which follows the closing of air inlet port 50 and the opening of fuel discharge port 54 to feed passage 18. If the engine is now "turned over" or cranked, some fuel will be drawn from the main nozzle 7 and be mixed with air admitted at port 6, which mixture will pass the throttle valve which has been automatically opened to the intermediate position indicated by the line c and be supplied to the engine cylinders. The fuel mixture passing the edge of the throttle will pick up or entrain the solid liquid fuel supplied direct from reservoir 10 via port 36, conduit 40, chamber 27, port 54, passage 18, and be discharged from port 20 above the throttle into the passing mixture stream to supply the desired "rich" mixture for engine priming or starting. When the engine fires and is started, the lever 45 may be and preferably is immediately returned, or permitted to return, under the force of spring 67 in a counter-clockwise direction, except in extremely cold weather, to the position of Fig. 4. As will be noted, movement of valve member 24 from the position of Fig. 5 to that of Fig. 4, causes the cam face 60 to act on the pin 61, forcing the pin outward against the force of spring 41, and in moving the pin moves the throttle therewith toward open position and to the position indicated by line b. When the throttle edge moves to point b' the valve ports 54 and 50 will remain closed, and port 55 will be brought into register with the nozzle conduit 21. In addition to the mixture of fuel and air discharged into the mixing chamber from the main inlets, there will now be a supplemental discharge of solid liquid fuel from the nozzle 23, which will mix with the main mixture and passing the open throttle valve will be fed to the engine cylinders. It is to be noted that with the throttle edge at the point b', the engine suction will be sufficiently transmitted to the vanes 5 to cause them to open somewhat, which will lift the main nozzle 7 relative to the valve 8 and so maintain a desired fuel ratio from the main air and fuel inlets, but this mixture ratio will not be rich enough in fuel for warming up the engine, so the deficiency in fuel is made up by the supplemental discharge from the nozzle 23, which is, however, less than the prior discharge from conduit 18. By providing the cam faces 59 and 60, which are operative to move the throttle to different positions, it is possible to automatically obtain the proper and most advantageous throttle positions for predetermined fuel to air ratios for engine starting and warming up. As the valve member 24 is moved from normal to the position of Fig. 4, thus causing a discharge of fuel through nozzle 23, the quantity of fuel supplied will be increased, thereby decreasing the ratio of air to fuel. When the valve member is moved from the position of Fig. 4 to that of Fig. 5, the fuel now discharged through the larger priming passage 18 will be further increased, thereby further decreasing the ratio of air to fuel.

When the engine has been "warmed-up", the lever 45 will be returned to the position of Fig. 3, which will permit the throttle to move under the force of spring 41 to normal idling position indicated by line a, and which will open ports 50 and 53, but port 53 will not supply fuel to the nozzle 23 as the suction thereon will be satisfied by the economizing air admitted to chamber 27 through port 50. As the throttle is gradually opened by lever 13, the plug valve 30 will finally cut down and close off port 50, thereby placing the fuel in the reservoir under the mixing chamber suction through nozzle 23 and causing a supplemental discharge of fuel, which, however, will be diluted by air entering the bleed port 57, which will have been moved into recess 29. Upon a quick movement of the throttle to open position, the piston 38 will force fuel from the pump chamber up the tube or conduit 40 into chamber 27 and thence through nozzle 23 to the mixing passage 2. Some of the fuel entering chamber 27 will be forced out or overflow through air inlet ports 50, 51 into the cup 47. This overflowing fuel will drain through passage 48 into recess 29 and enter port 57 to prolong the discharge of fuel from nozzle 23 and augment the supplemental supply which occurs when the port 50 is closed by plug valve 30, which follow-up structure or feature, however, is not of my invention.

The sizes and dimensions of ports and passages heretofore defined are particularly adapted, though not limited, for use in a carburetor having a mixing passage diameter of about one and one-half inches and a main nozzle jet or port diameter of about sixty-seven thousandths (0.067) of an inch.

What I claim and desire to secure by Letters Patent of the United States is:

1. A carburetor comprising a casing having a mixing passage with an air inlet thereto, means to supply fuel to said passage, a throttle controlling flow through said passage, means to regulate the fuel-air ratio in said passage, and means operatively connecting said regulating means and said throttle, said connecting means including means acting upon a decrease in the ratio of air to fuel to move said throttle toward an open position and including means acting upon a further decrease in the ratio of air to fuel to move said throttle toward closed position.
2. In a carburetor, a casing having a mixture passageway therethrough, means to supply fuel to said passageway, means controlling said supply means and being operable in one position to effect a predetermined supply of fuel and in another position to effect a predetermined increased supply of fuel, means to control flow through said passageway, and means responsive to operation of said first-named control means to move said second-named control means toward an open position as said first-named control means takes said one position and then to move said second-named control means toward closed position as said first-named control means takes said other position.
3. In a carburetor, a casing having a mixture passageway therethrough, means to supply fuel to said passageway, valve means controlling the discharge of fuel into said passageway, said valve means being operable in one position to permit a predetermined discharge of fuel and being operable in another position to permit a predeter-

- mined increased discharge of fuel, a throttle controlling flow through said passageway, and means operatively connecting said valve means and said throttle, said last-named means including means for moving said throttle toward open position when said valve means is moved to said one position and means for moving said throttle toward closed position when said valve means is moved to said other position.
10. 4. In a carburetor, a casing having a mixture passageway therethrough, a throttle controlling said passageway, a main fuel nozzle to supply fuel to said passageway, a fuel reservoir, a conduit communicating with said reservoir and discharging into said passageway, a valve controlling said conduit, said valve having a port of predetermined cross-sectional area and having a second port of larger cross-sectional area, means engaging said throttle and operable by said valve to move said throttle toward open position upon registration of said first-named port with said conduit, and means operable upon registration of said second-named port and said conduit to move said throttle toward closed position.
15. 5. A carburetor comprising a casing having a mixing chamber, main air and fuel inlets to said chamber, a throttle controlling the outlet from said chamber, a fuel reservoir, a fluid chamber, a conduit connecting said reservoir and said fluid chamber, a conduit connecting said chambers, a conduit from said fluid chamber to said outlet, valve means controlling said second-named and said third-named conduits, means for operatively connecting said valve means and said throttle, said connecting means including means acting to move said throttle toward open position when said valve means is moved to permit discharge through said second-named conduit and including means acting to move said throttle toward closed position when said valve means is moved to open communication between said first-named and said third-named conduits.
20. 6. A carburetor comprising a casing having a mixing passage with an air inlet thereto, means to supply fuel to said passage, a hollow valve member having a fluid chamber, a fuel reservoir, a passage from said reservoir to said chamber, said member having a plurality of ports opening from said chamber, conduits cooperable with said ports and discharging into said mixing passage, a throttle controlling flow through said mixing passage, a double cam operable by said valve member, means operatively connected to said throttle and engaging said cam, said cam acting upon movement of said valve member in one direction for successively alining said ports and conduits to move said throttle toward an open position and then toward a closed position.
25. 7. A carburetor comprising a casing having a mixing passage therein, a throttle controlling flow through said passage, means to supply air and fuel to said passage, a fuel reservoir, a conduit of said throttle, a conduit discharging into said passage on the inlet side of said throttle, said conduits receiving fuel from said reservoir, a valve controlling flow through said conduits, means operable by said valve for moving said throttle toward open position upon movement of
- said valve to permit flow through said second-named conduit, and means operable by said valve for moving said throttle toward closed position upon movement of said valve to permit flow through said first-named conduit.
8. In a carburetor, a casing having a mixture passageway therethrough, means to supply fuel to said passageway, means to control flow through said passageway, means to control the fuel supplied by said first-named means, means operatively connecting said second-named and said third-named means, said connecting means including means to actuate said second-named means to increase flow through said passageway upon operation of said third-named means to increase the fuel supplied to said passageway, and said connecting means including means to actuate said second-named means to decrease flow through said passageway when said third-named means is actuated to increase further the fuel supplied to said passageway.
9. A carburetor comprising a casing having a mixture passageway therethrough, means to supply fuel to said passageway, a housing, a hollow valve member rotatable in said housing and having a fluid chamber, a plurality of conduits extending from said housing and opening into said passageway, said valve member having a plurality of ports operable to establish communication between said fluid chamber and said conduits, one of said ports being of larger flow area than the other of said ports, means controlling flow through said passageway, cam means operable by said valve member, means operatively connecting said passageway control means and said cam means, said cam means acting upon movement of said valve member to register the other of said ports with one of said conduits to actuate said passageway controlling means to increase flow through said passageway, said cam means acting upon movement of said valve member to register the other larger port with another of said conduits to actuate said passageway controlling means to decrease flow through said passageway.
10. A carburetor comprising a casing having a mixture passageway therethrough, means to supply fuel to said passageway, valve means operable to vary the discharge from said supply means, a throttle valve controlling flow through said passageway, cam means operable by said valve means and cooperable with said throttle valve to regulate the position of said throttle valve, said cam means having diverging cam faces which substantially meet to form a cam high point, said faces being so related to said throttle valve and to said valve means that when said valve means is actuated to increase the discharge of fuel, the high point between said faces will cooperate with said throttle valve to move said throttle valve toward open position, and that when said valve means is actuated to increase further the discharge of fuel, one of said faces will cooperate with said throttle valve to permit said throttle valve to move toward closed position, and means normally tending to move said throttle valve toward closed position.

RUSSELL E. MACKENZIE.
